UNITED STATES PATENT OFFICE.

GEORGE EDGAR MAXFIELD, OF ROCKHAMPTON, QUEENSLAND, AUSTRALIA, ASSIGNOR OF ONE-HALF TO FRANK COUPER WOOSTER, OF ROCKHAMPTON, QUEENSLAND, AUSTRALIA.

WOODWORKING-MACHINE.

1,258,924.

Specification of Letters Patent. Patented Mar. 12, 1918.

Application filed December 16, 1915. Serial No. 67,099.

To all whom it may concern:

Be it known that I, GEORGE MAXFIELD, by occupation machinist, subject of the King of Great Britain, residing at General Hospital, Rockhampton, in the State of Queensland, Commonwealth of Australia, have invented new and useful Improvements in Improved Woodworking-Machines, of which the following is a specification.

10 This invention relates to an improved wood working machine and refers more especially to a machine for producing or dressing a number of wood forms such as table legs and the like of either square, oblong or octagonal or other shape from blanks. The machine may also be adapted to produce circular architraves moldings and the like and at the same time do the smoothing and finishing.

15 The object of this invention is to provide a machine in which a number of wood forms of any desired angular shape in cross section may be produced and finished off at the one time with greater facility and less labor and expense than can be done at present.

20 I accomplish these objects by providing a machine which comprises a revolving carrier which supports a number of wooden blanks upon its periphery, a series of saws for making the necessary cuts in the blanks, a series of revolving cutters for facing and dressing the said blanks, rotating mandrels of the required shape suitably faced with sand or powdered glass for smoothing, revolving brushes for finishing off, and also revolving grinders for sharpening the aforesaid cutters. I also provide an attachment to this machine whereby it may be adapted for producing circular architraves moldings and the like which comprises means for clamping a circular wooden blank upon the face of one of the disks of the aforesaid carriers in conjunction with rotating cutters of the required shape with corresponding finishing tools.

25 The invention will now be more fully described aided by a reference to the accompanying sheets of drawings in which—

Figure 1 is a side elevation,

Fig. 2 a plan and

Fig. 3 an end view of a machine constructed according to this invention, several parts being omitted in several of the figures for sake of clearness.

Fig. 4 is an elevation of one of the hinged sections of the carrier.

Fig. 5 is an enlarged view of the cutter head or carrier showing the knives or cutter holders in position thereon.

Fig. 6 is a rear view of one of the cutter holders.

Fig. 7 is a detail section of the carrier rim showing the means for securing the wood blanks in position on the rabbeted portion thereof.

Fig. 8 shows the means devised for supporting the wood blanks on the rabbeted rims of the carriers when the said blanks are to be milled octagonal shape or the like.

Fig. 9 is a front view and

Fig. 10 a sectional elevation of the adjustable support for one end of the grinder spindle.

Fig. 11 a detail view showing the means for mounting the grinder on its spindle.

Fig. 12 a diagrammatic view of the belt gearing for driving the various parts of the machine.

Fig. 13 is a side elevation showing the attachment to the machine whereby circular architraves or the like can be machined.

Fig. 14 an end section of the same.

Fig. 15 a detail view of the central supports for the trunnions and

Fig. 16 a view of the cutter adapted to form the bead of the circular architraves.

As shown in Figs. 1 to 12 A is the wood blank, B the circular saws, C the cutting tools, D the sander or finishing mandrel, E the revolving brushes and F the grinder. 1 is the frame of the machine made preferably in two main parts or portions the right side portion being rigidly fixed to the foundation and adapted to support the various gearing and working parts, while the left side portion of the said frame is capable of adjustment along the guide rails 1^a to suit the length of the wood blanks and to accommodate the attachment for enabling circular architraves to be produced. 2 is the main shaft of the machine supporting the carriers for the wood blanks A. This shaft is mounted at either end in adjustable or sliding bearings 3 supported on the machine frame and adapted to be moved along the said frame by chain and sprocket gearing 4 operating screw rods 5 connected to said bearings and controlled by the hand wheel

6 in order to bring the wood blanks A into contact with the saws B and the cutting tools C and afterward into contact with the sander or finishing mandrel D and brushes E.

5 The bearings 3 can be locked in any desired position by pivoted cams 6^a which are pivoted to short rods projecting down from the underside of the bearings and adapted to bear against the underside of 10 the projecting portion of the machine frame, in order to retain the wood blanks A in a proper position while being operated upon. The cams 6^a are operated and controlled by the rods 6^b and hand lever 6^c 15 which can be locked by the bolt 6^d passing through the slot 6^e in the quadrant 6^f.

The carriers or supports 7 for the wood blanks A are adjustably mounted upon the main shaft 2, the right side carrier member 20 being built up rigid, while the left side carrier is built up in sections of say four as shown. Each section or segment of the left side member has its supporting arms 8 hinged at 9 (see Fig. 4) in order to allow 25 each section to be swung back or opened as shown by dotted lines Fig. 3 to enable the whole periphery of the carrier to be filled with the blanks A. These carrier members 7 are furnished with rabbeted rims or ledges 30 10 adapted to support the wood blanks while each section of the left side carrier member is locked about the wood blanks A by draw rods which extend through each carrier member and furnished with turn buckles 12 35 and pivoted locking cams 13 as shown, thus firmly clamping the wood blanks endwise between the vertical portions of the rims of the carrier. The wood blanks A are further secured endwise in position between the carrier rims by projecting steel band blades or 40 the like 14 (see Fig. 7) attached to cleats or the like 15 which in turn are attached to the vertical portions of the rims of the carriers 7 by such as screws. These projecting 45 band blades 14 are arranged in concentric rings on the face of the right side carrier member and also extend the full length of each section of the left side carrier 7 and are adapted to be forced into the ends 50 of the wood blanks when the carriers 7 are closed or drawn together by the draw rods 11 thus the whole or any portion of the periphery of the rabbeted portion of the rim 10 can be filled with the wood blanks 55 A which are firmly held in position endwise by the aforesaid projecting band blades 14. In order to enable octagonal wood forms to be milled angular shaped wood blocks 10^a are secured to the rabbeted rims 60 10 and the wood blanks A supported between the said blocks 10^a as shown in Fig. 8. To prevent the wood blanks sagging at the center, a central support or carrier 65 16 is mounted on the main spindle 2 and furnished with a wood rim 17 upon which the

wood blanks A are supported as shown in Figs. 2 and 3. This central carrier 16 is made preferably in halves in order that it can be readily removed from the main shaft 2 when it is to be used for producing 70 circular architraves as will be hereinafter described.

The circular saws B which are adapted to produce the necessary cuts in the wood blanks in order to facilitate the operation 75 of the knives or tools C and to remove the surplus portion of the cut are mounted on a spindle 18 carried in bearings 19 mounted on the machine frame, the said saws C being held in the desired position on the spindle 80 18 between distance pieces or sleeves 20 and a locking nut 21. The swivel bearings 19 are supported on sliding brackets 22 mounted on the stepped portion of the machine frame and are capable of adjustment by the 85 screw rods 23 one end of each of which passes through a tapped lug 24 projecting down from each bracket 22 and the outer ends of said screws are furnished with sprocket wheels 25 having a connecting 90 chain 26 operated by the hand wheel 27 through the medium of the sprocket pinion 27^a. Thus the saws can be moved to or from the wood blanks A, while the bearings 19 being swiveled vertically enable one end 95 of the saw spindle 18 to be placed slightly in advance of the other end according to the cuts desired to be formed in the wood blanks A and to remove the surplus portion of the same.

The cutters or forming tools C which are of the desired shape according to the form to be produced, are mounted on holders 28 (see Figs. 5 and 6) having dove tail extension pieces 29 adapted to fit in dove tail 100 slots 30 formed in a circular revolving head piece or carrier 31 and held in position by set screws 32. These cutter heads or carriers 31 are securely mounted on a transverse spindle 33 at the requisite distance apart by set screws 33^a. The spindle 33 is mounted in bearings 34, that upon the right side having a dove tail base 35 adapted to slide in a similar shaped groove or slot 36 formed in the machine frame 1 and held in 105 position by bolts 37. The dove tail bases 35 and slots 36 enable the bearing 34 on the right side to be readily removed when it is desired to remove or replace the circular cutter heads 31 and knife holders 28.

The sander or finishing tool D is in the form of a suitable mandrel made from suitable composition molded to the desired shape or pattern and faced with sand or powdered glass. This sander or finishing 110 tool D is situated at the side of the machine to the cutters as shown and mounted on a spindle 37 carried in adjustable bearings 38 which can be adjusted by the screw rods 39 and hand wheel 40, the bearing brackets 38 115 120 125 130

being mounted upon a slide 41 adapted to move in a suitable slot 42 in the machine frame as shown in Fig. 2. The sander D is adjustably mounted upon the spindle 37 by a collar 43 at one end and a lock nut 44 at the other end. The revolving brushes E are formed with projecting bristles or steel wire secured to a wooden base securely mounted on a transverse spindle 45 carried in adjustable bearings 46 which are capable of being readily adjusted in order to set the brush E at the proper position.

The grinder F which comprises an emery wheel is supported on an adjustable spindle 47 above the cutting tools C as shown in Fig. 1 and is adapted to be utilized to grind the cutters C without having to remove the same from the machine. The said grinder is mounted on a sleeve 48 which is held in position with set screws 49 engaging a longitudinal slot 50 in the spindle 47 to enable the said grinder to be rotated and at the same time be moved into engagement with the cutters C by hand, for this purpose a loose collar 51 is mounted on the aforesaid sleeve 48 and prevented from moving longitudinally thereon by a pin or screw 52 fitting into an annular recess 53 in the sleeve 48.

To enable the grinder F to be placed at any desired angle to grind the cutters C the spindle 47 is made in two lengths connected together by a universal joint 54, and mounted at one end in a bearing 55 formed at the top of a pivoted telescopic standard 56 pivoted to the machine frame and capable of adjustment to suit the height of the spindle 47 and angle of the grinder F. The other end of the said spindle 47 is mounted in adjustable bearings 57 mounted on a suitable frame 58 which is hinged at 59 to the machine frame 1 as shown in Figs. 9 and 10. This frame 58 can be set at the desired angle by a screwed spindle 60 which passes through a tapped hole in a swivel block or like 61 pivoted at 62 to the frame 58 as shown, and operated by the hand wheel 63, the said screw spindle 60 being adapted to slide in a vertical slot 64 in the machine frame 1 and held in working position therein by convex collars 65 arranged one at either side of the frame 1 as shown.

In order to prevent the wood blanks A "chattering" while being operated upon by the cutters C (see Fig. 12) a friction roller 66 shod with india rubber or the like is mounted on a pivoted arm 67 and adapted to bear against the wood blanks A and force same against the rim 17 of the central carrier 16 by means of a suitable weight 68 and flexible connection 69, while to adjust the position of the said roller 66 a set screw 70 is adapted to bear against the underside of the machine frame.

A somewhat similar pressure roller 71 adapted to bear against the wood blanks A

is arranged in close proximity to the circular saws B and mounted on a pivoted arm 72 and operated by a flexible connection 73 and weight 74 and regulated by an adjusting screw 75 (Fig. 12).

Referring to Fig. 12 which is a diagrammatic view of the driving gear—100 is the main driving shaft driven from any suitable motive power, 101 the counter shaft driven from the main shaft 100 by the belt 102, this counter shaft 101 is adapted to operate the carriers 7 at different speeds, and for the purpose of a high speed the said shaft 101 is furnished with a sprocket pinion 103 operating a sprocket wheel 104 mounted on the main shaft 2 of the machine by the chain 105, a sliding clutch 106 (Fig. 2) being mounted on the said machine shaft 2 in order that the sprocket wheel 104 may be put in or out of gear with the counter shaft 101, the usual clutch lever being employed.

For the purpose of a slow speed drive for the carriers 7 a worm wheel 107 is loosely mounted on the shaft 2 and adapted to gear 108 with a worm 109 carried on a spindle 109 which is mounted in bearings 110 secured to the upper ends of adjustable vertical rods 111 passing through guide blocks 112 secured to the machine frame, the position of the worm spindle 109 being adjusted by the set screws 113 passing through the lugs 114 and locked in such position by the studs 115 in the guides 112. On the outer end of the worm spindle 109 is a loose driving pulley 116 which is driven from a pulley 117 on the counter shaft 101 by the belt 118.

The pulley 116 on the worm spindle 109 is furnished with a suitable friction clutch adapted to receive the sliding friction 105 clutch member 119 which is operated by the levers and rods 120. (See Figs. 1 and 2.) Thus it will be understood that the machine can be driven at either a comparatively high or low speed as desired.

In order to take up the slack of the sprocket chain 105 when the machine shaft 2 is moved along the frame 1 in order to bring the milled forms A into contact with the sander D an idle sprocket pinion 121 is provided mounted on the end of a pivoted lever 122 on the other end of which is an adjustable weight 123 adapted to cause the sprocket pinion 121 to take up the slack in the chain.

The revolving saw spindle 18 is driven from a counter shaft 124 by the belt 125 which passes about suitable tension pulleys 126 mounted on a hinged arm 127. This counter shaft 124 receives motion from the driven shaft 100 by the belt 128.

The cutting tool spindle 33 is driven from a separate counter shaft 129 by a belt 130 which also passes about tension pulleys 131 mounted on a hinged arm 132. This counter

70

110

115

120

125

130

shaft 129 is also driven from the main driven shaft 100 at the desired speed by the belt 133 as shown.

The sander spindle 37 is driven by a belt 134 from a shaft 135 the said belt passing about tension pulleys 136, this shaft 135 being driven from the main driven shaft 100 by the belt 137.

The revolving brush spindle 45 is also driven from the shaft 135 by the belt 138 which passes about idle or tension pulleys 139.

It will be understood that the various shafts are so geared to the main shaft 100 that the required speed is obtained for the tools.

The mode of operation is as follows:—

The wood blanks A say of square section and of the requisite length are placed in position upon the peripheries of the rabbeted portions 10 of rims of the carriers 7 and firmly locked by the cams 13. The carriers 7 are set in motion to the speed desired; then the revolving saws B are brought into operation by the hand wheel 27 in order that the necessary transverse cuts or incisions may be formed in the blanks A. After this operation the saws B are withdrawn and the carriers 7 brought forward by moving the bearings 3 by operating the hand wheel 6 until the wood blanks A come into contact with the cutting tools C and the blanks milled to the form desired on the one face.

The bearings 3 are then moved in the opposite direction along the machine frame by the hand wheel 6 until the carriers 7 are in the desired position for the sanders or finishing tools D and the brushes E to operate on the formed face of the blank.

The blanks A are then removed and replaced in position on the carriers in order that a fresh face is exposed to be operated upon as before described.

In order to adapt the machine for producing circular architraves or the like, the central carrier 16 is removed from its position between the carriers 7 and secured in position on the main shaft 2 near its outer end as shown in Fig. 14 and attached to the arms 50 of the said carrier is an annular ring 148 made preferably of wood and built up as shown and to which is suitably attached the circular wood blank 149 of such a shape in section to correspond with the architrave to be formed.

For the purpose of operating upon the circular wood blanks 149 an attachment is provided which comprises a pair of trunnions or shafts 150 rigidly mounted in the upper portion of pillars 151 and further supported about the center of their length by an adjustable hanger 152 and clamp 153 from the main shaft 2 (see Fig. 16).

The cutters or forming tools C are supported on circular heads or carriers con-

structed as before described while the spindle is mounted in adjustable bearings 154 having dove tail bases 155 fitting in similar shaped grooves in a sliding block 156 mounted on the trunnions or stationary shafts 150 and adapted to be held in any desired position thereon by such as set screws 157 while the position of the cutters C can be regulated by a rack 158 formed on the underside of the bearings 154 and gearing 75 with a rack pinion 159 operated by the hand wheel 160. The cutters C may be formed having members so as to produce any form of architrave such as shown in section in Fig. 14.

In order to form the return bead of circular architrave such as shown in the drawings a separate cutter C' (Fig. 15) is mounted on the trunnions 150 in a similar manner to the face cutters C but is adapted to operate at right angles to them as shown.

The sander D is also mounted in a similar manner to the cutters C and is capable of similar adjustment having the necessary rack 158 and pinion 159 operated by the hand wheel 160.

I claim:—

1. In a wood working machine the combination of a frame, a revoluble carrier journaled on the frame and comprising a rigid section and a section having hinged segments, said sections having rabbeted peripheral portions adapted to receive wood blanks of polygonal cross section, rods having cam elements connecting said rigid and segmented sections and adapted to hold the wood blanks on said sections, members carried by the segmented section adapted to penetrate the wood blanks at the ends thereof and secure the same against displacement, 100 saws and cutters for acting on the wood blanks, and means for moving the carrier to bring the blanks to engage said saws and cutters, substantially as described.

2. In a wood working machine the combination of a frame, a revoluble carrier journaled on the frame and comprising a rigid section and a section having hinged segments, said sections having rabbeted peripheral portions adapted to receive wood blanks of polygonal cross section, draw rods connected to said rigid section having turn buckles for adjusting the same, cam members carried by the draw rods engaging with said hinged segments to hold the wood 110 blanks on said sections, members carried by the segmented section adapted to penetrate the wood blanks at the ends thereof and secure the same against displacement, 115 saws and cutters for acting on the wood blanks, and means for moving the carrier to bring the blanks to engage said saws and cutters, 120 substantially as described.

3. In a wood working machine the combination of a frame, a shaft journaled on 130

the frame; a wood blank carrier mounted on said shaft comprising a rigid section, and an adjustable collapsible section; said sections constructed to receive wood blanks of 5 polygonal cross section, tie rods having cam elements for holding said sections and the wood blanks in assembled relation, a central carrier adjustably mounted on the shaft between said sections adapted to engage with 10 and brace the wood blanks during working, cutters and saws for working on said wood blanks, and means for moving the carrier to bring the wood blanks to engage said saws and cutters, substantially as described. 15

4. In a wood working machine, the combination of a frame, a shaft journaled on the frame, a revoluble carrier mounted on said shaft comprising a rigid section, and a section having hinged segments, said sections having rabbeted peripheral portions 20 adapted to receive wood blanks of polygonal cross-section; a central carrier mounted on

the shaft between said sections and adapted to support said blanks, adjustable draw rods connected to the rigid section and passing through said central carrier and the segmented section, cam members carried by the draw rods engaging with said hinged segments to hold the wood blanks on said sections, blades carried by the segmented section adapted to penetrate the wood blanks at the ends thereof and secure the same against displacement, saws and cutters for acting on the wood blanks, and means for moving the carrier to bring the blanks to engage said saws and cutters, substantially as described. 25 30 35

In testimony whereof I have signed my name to this specification in the presence of two subscribing witnesses.

GEORGE EDGAR MAXFIELD.
